UNITED STATES PATENT OFFICE.

GEORGE N. HEIN, OF SAN FRANCISCO, CALIFORNIA.

OPERATING MECHANISM FOR SUNSHADES AND THE LIKE.

Application filed October 8, 1923. Serial No. 667,180.

To all whom it may concern:

Be it known that I, GEORGE N. HEIN, a citizen of the United States, residing at the city and county of San Francisco and State 5 of California, have invented certain new and useful Improvements in Operating Mechanism for Sunshades and the like, of which the following is a specification.

This present invention relates to an operating means for adjusting members of 10 different types such as awnings, vehicle windshields or sunshades; in fact, any body which it is desired to roll or which is mounted for pivotal adjustment.

15 The invention consists in providing at least two members one mounted for axial rotation and held from longitudinal movement, and the other held from axial rotation and mounted for longitudinal movement, 20 the members being interconnected by an operating pin engaging with the axially rotatable member through a slot disposed obliquely to its axis of rotation, the member to be operated either adapted for winding 25 around the rotating member or secured at one edge thereto to extend radially therefrom; the longitudinal movement of the member capable of this operation imparting axial rotation to the other member.

30 The embodiment illustrated comprises a compact installation consisting of three nested rods, the outer adapted for axial rotation and held from longitudinal movement and provided with oblique slots, the 35 nest innermost being held from longitudinal movement and axial rotation and provided with longitudinal guide slots and the innermost or operating member adapted for longitudinal movement and provided with operating pins for extending through the slots 40 of the other two respective rods whereby on the operation of the innermost member axial rotation will be imparted to the outer member to cause any part carried thereby to move therewith.

45 With the above mentioned and other objects in view, the invention consists in the novel construction and combination of parts hereinafter described, illustrated in the accompanying drawings, and set forth in the 50 claims hereto appended, it being understood that various changes in the form, proportion, size and minor details of construction within the scope of the claims may be resorted to without departing from the spirit

or sacrificing any of the advantages of the invention.

In the drawings, Fig. 1 is a view in plan of one embodiment of my invention the same illustrating its adaptation to an adjustment for vehicle sunshades.

Fig. 2 is a view in rear elevation.

Fig. 3 is a view taken on line 3—3 of Fig. 4.

Fig. 4 is a longitudinal sectional view, and 65

Fig. 5 is a cross sectional view on line 5—5 Fig. 1.

In the embodiment illustrated 1 indicates a pair of spaced end supporting members between which is held from axial rotation 70 and from longitudinal movement a tubular guide rod. The guide rod is provided with a pair of longitudinal aligned guide slots 3 into each of which projects an operating pin 4 extended laterally from a longitudinally 75 movable operating rod 5 positioned within the rod 2. The rod 2 is formed with a cut out portion 6 through which is adapted to extend an operating handle 7 connected with the rod 5. The handle 7 has a bent portion 80 enabling the recess 9 formed thereby to receive the top edge of a vehicle windshield frame and admitting of the brackets 1 being positioned at a point below the upper edge 85 of the frame, to admit of a vehicle top to lie in close proximity to the upper edge of the shield. Surrounding the supporting rod 2 between the members 1 which hold the same from longitudinal movement is an axially rotatably tubular rod 10. In the ill- 90 lustration this rod is connected as at 11 with one edge of a sunshade 12 disposed longitudinally thereof and extending radially therefrom. The rotatable rod 10 is provided with a pair of oblique channels 13 therein 95 extending across the channels 3 and into these channels 13 also extend the pin 4.

The device being assembled as in the drawing the illustrated embodiment operates in the following manner. The handle 7 extending rearwardly of the vehicle windshield and at right angles approximately midway of its upper edge is grasped by the vehicle operator and a movement is imparted thereto to cause the operating rod 5 to move 100 longitudinally of the guide 2. This movement causes the pins 4 guided in the slots 3 to bear against the edges of the slots 13 and cause axial movement to be imparted 105 to the outer tube 10 which will cause a 110

raising or lowering of the free edge of the sunshade 12.

While I have illustrated this one embodiment and have shown the same as being adapted for association with the vehicle windshield it is to be understood that other means than the handle 7 may be employed for imparting longitudinal movement to the tube 5 and also that in place of a sunshade 12 a flexible member or awning could be secured to the outer tube 10.

What I claim is:

1. In combination with a tubular rod supported at its ends for axial rotation and held from longitudinal movement, said rod provided with a slot disposed obliquely to its axis of rotation, a member movable longitudinally within the rod and cooperating with the rod and held from axial rotation, a pin carried by said member and receivable in said slot, means for moving said member longitudinally to impart axial rotation to the rod, and a sunshade extending radially from said rod and secured at one edge thereto.
2. In combination with three nested rods, at least two of which are tubular, one of the latter being held from axial rotation and the other mounted for free axial rotation and held from longitudinal movement, said tubular rods being provided with superimposed slots arranged at an angle to each other, the third rod being longitudinally movable and provided with an operating pin projecting outwardly through the slots in the other two rods, means for moving the third rod longitudinally, and a sunshade associated with the axially rotatable rod.
3. In combination with three nested rods, at least two of which are tubular, one of the latter being held from axial rotation and the other mounted for free axial rotation and held from longitudinal movement, said tubular rods provided with registering cut away portions and further provided with slots

disposed in angular superimposed cooperating relation, the third rod being longitudinally movable and provided with a pin projecting upwardly through said slots, means engaging the third rod for imparting reciprocating movement thereto and extending through said cut away portions, and a sunshade secured at one edge to and extending radially from the axially rotatable rod.

4. In combination with three nested rods, at least two of which are tubular, one of the latter being held from axial rotation and the other being free for axial rotation and held from longitudinal movement, said tubular rods provided with slots disposed in superimposed relation, the slot of the axially rotatable rod being disposed at a right angle to its axis, and the slot of the fixed rod being parallel with its axis, the innermost rod being longitudinally movable and provided with a pin for extending into said slots, means for moving the innermost rod longitudinally, and a sunshade associated with the axially rotatable rod.

5. In combination with three nested rods, at least two of which are tubular, one of the latter being held from axial rotation and the other being free for axial rotation and held from longitudinal movement, said tubular rods provided with registering cutaway portions and further provided with slots disposed in superimposed relation, the slot of the axially rotatable rod being disposed at a right angle to its axis, and the slot of the fixed rod being parallel with its axis, the innermost rod being longitudinally movable and provided with a pin for extending into said slots, means for moving the innermost rod longitudinally and a sunshade secured at one edge to the axially rotatable rod and extending radially therefrom.

In testimony whereof I have signed my name to this specification.

GEORGE N. HEIN.
